RECORD FORM HANDLING DEVICE

William M. Carroll, Dayton, Ohio, assignor to
 The National Cash Register Company, Dayton,
 Ohio, a corporation of Maryland

Application October 28, 1941, Serial No. 416,919

2 Claims. (Cl. 271—18)

This invention relates to positive means for permitting the removal of only the top sheet from a stack of record material sheets during an operation of the machine, and electro-magnetic means for removing the top sheet from the stack and placing it in cooperative relationship with adjacent feeding mechanism.

The present invention contemplates means for overcoming difficulties frequently experienced with several sheets being accidentally and simultaneously removed from the top of a stack of such sheets when the sheets should be removed singly therefrom. In order to obviate this condition the present invention provides positive means for releasing only the top sheet for removal from the stack of sheets during each operation of the machine. In addition, electro-magnetic means is provided for removing such released sheet from the top of the stack and placing such sheet in cooperative relationship with adjacent feeding mechanism.

It is, therefore, a primary object of this invention to devise positive means for permitting only the top sheet to be removed from a stack of sheets during an operation of the machine.

Another object is to devise means for removing only the top sheet from a stack of sheets during each operation of the machine.

A further object is to devise means for permitting the removal of only the top sheet from a stack of sheets, and means operating in conjunction with the first mentioned means to remove the top sheet from the stack and place it in cooperative relationship with adjacent feeding mechanism.

A still further object is to devise a record material sheet provided with variably located notches, and means coacting with the notched and unnotched portions of the sheets to prevent any sheet, except the top sheet, from being removed from a stack of such sheets during an operation of the machine.

An additional object is to provide a record material sheet bearing on one side thereof magnetically attractive material by which an electro-magnetic means can remove said sheet from the top of a stack of such sheets.

Another object is to provide a plurality of record material sheets, each having one edge thereof notched in different locations, said sheets being so arranged in a stack that sheets bearing different notch arrangements will occur in alternating order, and means adapted to cooperate with the notches in the sheets to control the release of

only the top sheet in said stack for removal therefrom.

With these and incidental objects in view, the invention includes certain novel features of construction and combinations of parts, the essential elements of which are set forth in appended claims and a preferred form or embodiment of which is hereinafter described with reference to the drawings which accompany and form a part of this specification.

In the drawings:

Fig. 1 is a vertical section, taken on line 1—1 of Fig. 2, looking toward the right, showing the means for controlling the release of the top sheet from the stack for removal therefrom, the electro-magnetic means, and the means for operating both of the first two mentioned means.

Fig. 2 is a top or plan view of a portion of the means shown in Fig. 1.

Fig. 3 is a detail side view of the electro-magnetic means and mechanical means for rocking the same.

Fig. 4 is a diagrammatic view of the means for closing the circuit to energize the magnets.

Fig. 5 is a perspective view of three record material sheets, showing the different notch arrangements used on said sheets.

Briefly, the particular embodiment of the invention illustrated in the drawings makes use of record material sheets, one edge of each of which is provided with a group of notches variably located thereon. The sheets are so arranged in a stack that sheets bearing differently located groups of notches will occur in alternating order.

Two pairs of retaining members are provided, each pair corresponding to a different one of said variably located groups of notches, for normally holding all of the sheets against removal from the stack. Means is also provided for alternately actuating the different pairs of retaining members to release the top sheet for removal from the stack and retain the remainder of the sheets in the stack during each operation of the machine.

When one pair of retaining members is actuated to release the top sheet for removal from the stack, the other pair of retaining members which is not actuated coacts with the sheet next to the top sheet to prevent removal thereof from the stack.

Provided on one side of the record material sheets is a suitable magnetizable material such as, for example, magnetic ink or metallic strips to enable electro-magnetic means to properly attract thereto for removal from the stack. Upon being energized the electro-magnetic means will

draw the released top sheet thereto, whereupon the magnetic means, together with said sheet, are rocked clockwise, by means to be later described, to position the removed sheet into cooperative relationship with adjacent feeding mechanism. Upon being deenergized, the magnetic means will release the removed sheet, after which said means is rocked counter-clockwise to its home position. Mechanical means is provided for closing a circuit to energize the magnetic means and for opening the same circuit to deenergize such means.

Referring now to the drawings, suitable record material sheets 61 (Figs. 1 and 5) are arranged in a stack on a platform 62 supported by a plunger 63 slidably mounted in a cylindrical shaped housing 64 secured to a base plate 65 of the machine. A coil spring 66 contained in the housing 64 coacts with the plunger 63 to constantly exert upward pressure on the plunger and platform 62, thereby maintaining the top sheet 61 in the stack always in contact with the retaining members to be later described. A guide plate 67 having a pair of flanges 68 (only one of which is shown), one being formed on each side of said plate and at right angles thereto, coact with three different edges of the sheets to assist in maintaining them in proper alignment. The plate 67 is secured at its lower end to the base plate 65. Coacting with the remaining edges of the sheets 61 is another guide plate 69 provided with flanges 70 and 71 formed at right angles thereto and loosely mounted on a shaft 72 suitably journaled in side frames 73 and 74 secured to the base plate 65. The plate 69 is adapted to be manually moved a short distance counter-clockwise about the shaft 72 to facilitate the insertion of the stack of sheets 61 into the magazine created by the platform 62 and guide plates 67-69.

The plate 69 is maintained in its normal position as viewed in Fig. 1 by a latch 75 secured to a short shaft 76 suitably journaled in the frame 73. The latch is notched to engage lug 77 integral with the plate 69 to hold the plate in the position shown. Also secured to the shaft 76 is a lever 78 having a knob 79 by which the lever may be manually rocked clockwise against the action of spring 80 to disengage the latch 75 from the lug 77 to permit the plate 69 and associated parts to be later described, to be moved counter-clockwise for the purpose of inserting a new supply of record material sheets into the magazine.

Means provided for permitting the removal of only the top sheet from the stack of sheets in the magazine during each operation of the driving and feeding means including two pairs of retaining bars 85 and 86, Fig. 2, having flanges 87 and 88 respectively. Secured to flanges 87 and 88 are fingers 89 and 90, respectively, having secured to their undersides friction pads 91 and 92, respectively, adapted to contact the top two sheets 61 in the stack in the magazine.

The bars 85 and 86 (Figs. 1 and 2) are slidably and pivotally mounted on shaft 72 by means of vertical slots 93 through which said shaft extends. Each of said bars also has a vertical slot 94 engaged by a stud 95 carried by an angle plate 96 secured to plate 69, there being one plate 96 for each of the bars 85 and 86. Springs 97, fast at one end to studs 95 and at their other ends to studs 98 in the bars 85 and 86, constantly tend to move said bars and their fingers 89 and 90 upwardly, thus retaining rollers 99 in

contact with the peripheries of cams 100 and 101.

The cams 100 have high sections 102 and low sections 103, and the cams 101 have high sections 104 and low sections 105. When the high sections coact with the rollers 99, the bars 85 and 86 will be held down against the action of the springs 97. When the cams are rotated, a half rotation for each operation of the machine by means to be hereinafter described, the high sections are alternately removed from cooperative relation of the rollers 99, and the low sections are alternately brought into cooperative relation with said rollers, and consequently bars 85 and 86 are alternately released for upward movement by their springs 97.

As previously mentioned, the sheets 61 are notched alternately, and by referring to Fig. 5 it will be noticed that the top sheet here shown has two notches 106 arranged substantial distances in from the sides of the sheets, and that the second sheet has two notches 107 arranged nearer the edges of the sheets than are the notches 106.

Assuming that the sheets 61 are arranged in the stack with the two sheets of Fig. 5 on top, then the fingers 90 and their friction pads 92 will cooperate with the notches 106 and bear against the unnotched portions of the second sheet 61, and the fingers 89 and their friction pads 91 will cooperate with the unnotched portions of the top sheet 61 which lie immediately above the notches 107 of the second sheet.

With the parts in the positions just described, when the shaft 72 and the cams 100 and 101 are given a half rotation in a clockwise direction, the high sections 102 of the cams 100 will be moved away from the rollers 99 and the springs 97 will draw the rollers 99 into contact with the low sections 103 of the cams 100, thus raising the fingers 89 and their pads 91 to free the top sheet 61. The rollers 99 of the bars 86, at this time being in contact with the high sections 104 of the cams 101, the fingers 90 and their friction pads 92 will not be raised, and consequently will retain the second sheet in the normal position while the top sheet, having been released by the fingers 89, will, by means to be hereinafter described, be moved to the right as viewed in Fig. 1 to present it to feed rollers, to be hereinafter described, whereupon this top sheet will be completely removed from the stack after it has been presented to the feeding rollers.

Upon the next half turn of the shaft 72 and the cams 100 and 101, the high sections 102 of the cam 100 will be in constant contact with the rollers 99, and therefore the fingers 89 and their pads 91 will be retained in contact with the bottom sheet shown in Fig. 5 (which now, due to the fact that the top sheet has been removed, becomes the second sheet of the stack), and the low sections 105 of the cams 101 will be presented to the rollers 99, and consequently the springs 97 will raise the fingers 90 and their pads 92 to release what is now the top sheet (the middle sheet shown in Fig. 5), so that it can be removed from the stack without disturbing the third sheet in the stack (the bottom sheet shown in Fig. 5).

From the above description it will be clear that the two pairs of retaining bars 85 and 86 and their associated fingers 89 and 90, respectively, control the alternate release of a single sheet from the top of the stack of sheets shown in Fig. 1 with the cooperation of the alternate arrangement of the notches 106 and 107 in the sheets 61.

As previously mentioned, the shaft 72 and the

cams 100 and 101 receive one-half of one complete clockwise rotation during each operation of the machine. The means for imparting such movement to the shaft 72 will now be described.

The present machine is provided with a drive shaft 112 (Figs. 1 and 2), journaled in the side frames 73 and 74, which is given one complete counter-clockwise rotation during each operation of the machine by any suitable means. Secured on the shaft 112 is a gear 113 which is connected through gears 114, 115 and 116 to the shaft 72. The ratio between the gear 113 and the gears 114—115—116 is such that one complete rotation of the gear 113 will impart only one-half rotation to the gears 114—115—116. Therefore, when the shaft 112 and gear 113 are given one complete counter-clockwise rotation, the shaft 72 and all parts secured thereto are driven one-half rotation in a clockwise direction.

The electro-magnetic means for removing the top sheet 61 from the stack of sheets includes a pair of magnets 121 (Fig. 4) pivoted on a rod 122 (Figs. 1 and 2) carried by arms 123 and 124, pivotally mounted on a rod 125 secured in the side frames 73 and 74. The magnets 121 are normally located so as to be in cooperative relationship with the top sheet 61 of the stack of sheets. The means for energizing the magnets 121 to effect the removal of the top sheet from the stack will now be described.

During the counter-clockwise movement of the drive shaft 112, a cam 126 secured thereon will close a pair of contacts 127 and 128 (Figs. 1 and 4) to energize the magnets 121 over a circuit extending from one side of a suitable source of supply through a line 129, contact 128, contact 127, line 130, magnet 121, and line 131, back to the other side of said supply.

The record material sheets 61 have provided on their upper sides magnetizable material of any suitable character, such, for example, as magnetic ink or metallic strips 120 (Fig. 5), through which the magnets 121, upon being energized, can attract thereto the top sheet 61 of the stack of sheets. Immediately after this occurs, another cam 141 (Fig. 3), secured on the shaft 112, coacts with a roller 142 on a pitman 143, which is hook-shaped at one end to embrace the shaft 112 and is pivoted at its other end to the arm 123, to cam the pitman 143 toward the right. Such movement of the pitman 143 toward the right will rock the arm 123, together with the magnets 121 and the sheet 61 magnetically attached thereto, clockwise about the rod 125, against the action of a spring 144, to position the sheet 61 between the feed rollers 145 and tension rollers 146 (Fig. 1).

Immediately after the magnets 121 have moved the sheet 61 between the feed rollers 145 and tension rollers 146, another cam 147 secured on the shaft 112 will be moved to permit the tension rollers 146 to be moved into cooperative relationship with the feed rollers 145 to feed the slip 61 to the desired printing position. This is accomplished in the following manner.

The high spot on the periphery of the cam 147 normally coacts with a roller 148 carried by an arm 149, pivoted on a rod 150, to hold the arm in an ineffective position, as shown in Fig. 1. Another arm 151, also pivoted on the rod 150, serves in conjunction with the arm 149 to support a rod 152 upon which the tension rollers 146 are freely mounted. A spring 153 constantly tends to rock the arm 149 counter-clockwise to position the rollers 146 into cooperative relationship with the feed rollers 145, but is restrained from doing so

by the high portion of the periphery of the cam 147. It will therefore be seen that when the cam 147 moves sufficiently counter-clockwise to remove its high portion from beneath the roller 148, the spring 153 will then move the tension rollers 146 into cooperative relationship with the feed rollers 145 to feed the paper sheet 61.

The feed rollers 145 (only one of which is shown) are secured to a shaft 161 (Fig. 1) suitably journaled in the side frames 73 and 74. Also secured to the shaft 161 is a pinion 162, meshing with a gear 163 secured to the main drive shaft 112. During the counter-clockwise movement of the shaft 112, the gear 163 moves the pinion 162, shaft 161, and feed rollers 145 clockwise. It is not until the tension rollers 146 are moved into cooperative relationship with the rotating feed rollers 145 that the inserted slip 61 will be fed by said rollers.

Just before the tension rollers 146 are moved into cooperative relationship with the feed rollers 145, the cam 126 will release the pressure on the contact 127 sufficiently to allow the latter to spring apart from the contact 128, thereby opening the circuit and deenergizing the magnets 121, which will release the sheet 61 between the feed rollers 145 and tension rollers 146.

At this time the cam 141 (Fig. 3) will permit the spring 144 to rock the arms 123—124, magnets 121, and pitman 143 counter-clockwise to their home position.

While the form of mechanism herein shown and described is admirably adapted to fulfill the objects primarily stated, it is to be understood that it is not intended to confine the invention to the one form or embodiment herein disclosed, for it is susceptible of embodiment in various forms, all coming within the scope of the claims which follow.

What is claimed is:

1. In a machine of the class described adapted to coact with a stack of record material sheets, the combination of a plurality of means mounted for longitudinal and pivotal movement on a common shaft; a finger on each of said means, said fingers arranged to extend over the surface of the upper sheet of said stack; cams on the common shaft arranged to alternately raise and lower said plurality of means to first engage one finger with the second sheet from the top of said stack and then engage another finger with the second sheet from the top of said stack; means to remove the upper sheet from the stack when the fingers engage the second sheet from the top of the stack, said sheets being suitably notched to permit the fingers to engage the second sheet from the top of the stack; and a latch to normally maintain the fingers in proper relationship with the stack of sheets, said latch being operable to release the fingers to their pivotal movement to withdraw the fingers from said normal position to facilitate placing a stack of sheets in the machine.

2. In a machine of the class described adapted to coact with a stack of record material sheets, the combination of a plurality of means mounted for longitudinal and pivotal movement on a common shaft; a finger on each of said means, said fingers arranged to extend over the surface of the upper sheet of said stack; cams on the common shaft arranged to alternately raise and lower said plurality of means to first engage one finger with the second sheet from the top of said stack and then engage another finger with the second sheet from the top of said stack; means to

remove the upper sheet from the stack when the fingers engage the second sheet from the top of the stack, said sheets being suitably notched to permit the fingers to engage the second sheet from the top of the stack; a rocking frame also pivoted on said common shaft; a means on the rocking frame to guide the plurality of means when moved by said cams; and a latch coacting

5 with the frame to maintain the fingers in proper relationship with the stack of sheets, said latch operable to release the frame and the fingers to their pivotal movement to withdraw the fingers to facilitate placing a stack of sheets in the machine.

WILLIAM M. CARROLL.
